Attorneys.

UNITED STATES PATENT OFFICE.

JACOB ZWICK, OF NEUSTADT-ON-THE-HAARDT, GERMANY.

NAILBRUSH.

Application filed March 24, 1925, Serial No. 17,988, and in Germany November 5, 1924.

Good work of a brush depends upon the bristles retaining their original stiffness and elasticity, which they will do only when allowed to become clean and dry after use. In known brushes having rows of bristles facing each other at an angle, no provision is made for draining soap and water from the brushes and they are likely to become filthy and are subject to rapid decay. Moreover, in such brushes, the inner rows of bristles which are subjected to the hardest usage are the ones which are most quickly destroyed by dampness and filth. Such brushes are open to the objection that the useful life of the inner rows of bristles is much less than that of the outer rows.

An object of the invention is to provide a nail cleaning brush which will be free from the objections stated above. An object of the invention is to provide a brush having opposed rows of bristles arranged upon open frame members which allow the free passage of soap and rinsing water, and which admit air to the bristles to dry the same. A further object is to provide a brush as stated above, in which the bristles and frame are so correlated that water will quickly drain from the brush when it is placed upon a level surface. A further object of the invention is to provide a brush in which all of the bristles have substantially the same effective life. More specifically an object of the invention is to provide a brush having opposed rows of bristles and in which brush the inclination of the opposed rows may be varied to bring each row into the most effective position to perform its work.

Several constructions of the brush according to the invention are more or less diagrammatically illustrated in attached drawings.

Fig. 1 shows a nail-brush of the type including a finger guiding brush section and a cleaning section.

Fig. 2 is an end view of a brush consist-

ing of two sections, each with two rows of bristles connected by a metal plate.

Fig. 3 is a side view of the connecting part of sheet metal of the brush sections of Figure 2.

Fig. 4 is an end view of a further embodiment of the brush with a modified connecting member of the sections allowing every single row of bristles to be adjusted in its position to the other one.

Fig. 5 shows a construction where the two sections of the brush are linked together by connecting part to which bristle holders are reversibly fixed by pivot.

Figure 6 shows the brush sections in inoperative position.

Figures 7 and 8 shows, the former in end view and the latter in plan with the sections connecting parts in section, a modification of the construction of Figures 5 and 6.

In Fig. 1 of the drawings, the numerals 1, 2 designate the brush backs which serve as holders or supports for two groups of bristles. The back 1 carries two rows of bristles, the outer row 3° functioning to clean and massage the cuticle while the inner row 3ⁱ so guides the nail that the bristle of row 4ⁱ, carried by back 2, will clean under the nail. Row 4ⁱ also serves as a guide for positioning the finger tips to bring the cuticle opposite the bristles of row 3°.

As indicated in Fig. 2, the backs 1 and 2 may be fixed in position by bridge members 5 of sheet metal, and preferably an outer row 4° of bristles is mounted upon back 2.

The inner rows of bristles 3ⁱ and 4ⁱ wear out more quickly than the outer ones. Using very strong, elastic and lasting bristles for the hardworking inner rows 3ⁱ and 4ⁱ and softer and weaker bristles for outer rows 3° and 4°, for the easier work of cleaning cuticle, provides a construction in which all rows of bristles may be expected to be worn out at the same time. In this case the reversibility of brush backs 1, 2 illustrated in further fig-

ures may be dispensed with and the bristle holding frame may be shaped for instance out of one piece of celluloid, or other suitable material.

5 A better way to overcome the difficulty of uneven wear of bristles consists according to the invention in taking care for reversibility of the bristle rows in such way that formerly inner rows 3¹ and 4¹ serve as outer rows, the 10 original outer rows 3⁰ and 4⁰ now being used as inner rows.

The connecting members 5 of the brush shown in Fig. 2 may be removably secured to the backs by nails or the like which pass 15 through perforations in the metal connecting plates, or the connecting members 5 may be provided with teeth 6, as shown in Fig. 3, for securing the same to the backs. After removing connecting link 5 simply reverse brush sections bringing formerly outer rows 3⁰ and 4⁰ to serve as inner ones and 3¹ and 4¹ to serve as outer rows.

In Figure 4 each row of bristles is fixed into a separate backing, the rows 13¹, 13⁰ of the 20 one brush section into bars 1¹, 1⁰ and the bristle rows 14¹, 14⁰ into bars 2¹, 2⁰. The different ledges are kept in position by two linking parts consisting of two legs of a right angled member, the legs fitted with screw threads 7, 25 8, each ledge being adjusted and kept in position by screw nuts, bar 1⁰ by nuts 9, 9; ledge 1¹ by nuts 10, 10 and bars 2⁰, 2¹ by nuts 11, 12 respectively. The drawing shows clearly 30 how easily in this construction the different rows may be exchanged with each other, reversed and adjusted into just a right position according to size of nail.

Figure 5 shows a very simple construction 35 wherein the bristle backs 1', 2' are pivoted at both their ends to connecting links 13 (the link at one end only being shown), the pivots 14 lying substantially in the respective medial planes of the rows of bristles of the brush sections 1, 2. This symmetrical arrangement 40 of the pivots with relation to the rows of bristles allows interchanging of inner and outer rows of bristles by simple turning of parts 1', 2' through an angle of about 90° as shown in dotted lines. Abutments 15¹ and 45 15⁰ secure proper working position for bristle rows 23¹, 24¹ and 23⁰, 24⁰ respectively. At the same time in a brush construction as Figure 5 bristle holding backings 1', 2' may be turned 50 about 45 degrees after use, and the brush thus 55 may be brought into a suitable position to be packed for travelling as Figure 6 shows.

Of course in construction Figure 5 each of the backs 1', 2' may also be split in two halves 60 fixed to the pivots by screws and adjusted to size of nails and kept in position by screw nuts. In this case the connecting link 13 may also be made adjustable to regulate distance 65 in such a way that inner bristle rows only touch but need not intermix brushing sur-

faces at the junction line of the right dihedral angle formed by the end surface of the respective rows of bristles. This construction is illustrated in Figures 7 and 8 where 16, 17, 70 18, 19 designate four bars, each provided with one row of bristles, the bars being in pairs screwed to pivot plates 20, 21, said pivot plates provided with slots 22, allowing the bars of each of the two pairs to be adjusted according to size of nails. The pivot plates 75 20, 21 are pivoted to a connecting link consisting of two plates 23, 24 adjustable with relation to each other for instance by pin and slot connection as shown.

What I claim is:—

1. In a nail brush, a pair of brush backs 80 providing a finger guiding section and a cleaning section, groups of bristles carried by each of said backs with the ends of the bristles of each group terminating substantially in a single plane at right angles to the length of the bristles of the respective groups, and bridging members connecting the respective adjacent ends of said supporting backs to space the same apart and leave an 90 open slot of substantial width therebetween.

2. The invention as claimed in claim 1 wherein said sections are adjustably connected by means effective to hold the sections 95 against angular movement when the working surfaces are substantially normal to each other.

3. A nail brush comprising a pair of brush backs each provided with groups of bristles, and means connecting said backs to permit 100 positioning of the same with the respective groups of bristles at an angle to each other, said backs and connecting means having co-operating parts permitting relative rearrangement of the backs to bring different 105 edges of the respective groups of bristles into proximity to each other and to position the said groups with their working surfaces substantially normal to each other.

4. A nail brush comprising a pair of brush backs, each provided with groups of bristles, means pivotally connecting the said backs to permit the positioning of the bristles of the respective groups at an angle to each other, and means limiting the angular movement of said backs to two alternative positions in each of which the groups of bristles are substantially normal to each other. 110

5. A nail brush comprising a pair of backs, links pivotally supporting said backs and permanently spacing the same from each other, bristles on the respective surfaces of said backs which are presented towards each other, said bristles being of such length as compared to the spacing of said backs that the bristle-bearing surfaces may be turned 120 towards and past parallelism with each other, and means limiting the pivotal movement of each of said backs to an angle of substantially 90°. 125

6. The invention as claimed in claim 5,
wherein the working-surfaces formed by the
bristles of the respective backs are arranged
to lie normal to each other at the two alter-
5 native end positions of movement of the said
brush backs.

7. The invention as claimed in claim 5,
wherein the bristle lengths are such that the
adjacent edges of the working surfaces of
10 the two sets of bristles substantially coincide
at two alternative end positions of adjust-
ment of the said brush backs.

In testimony whereof, I affix my signature.
JACOB ZWICK.
